UNITED STATES PATENT OFFICE.

EUGENE E. STUVER, OF BLUE MOUND, ILLINOIS.

AXLE AND BEARING.

SPECIFICATION forming part of Letters Patent No. 634,774, dated October 10, 1899.

Application filed April 29, 1899. Serial No. 715,043. (No model.)

To all whom it may concern:

Be it known that I, EUGENE E. STUVER, a citizen of the United States of America, residing at Blue Mound, in the county of Macon 5 and State of Illinois, have invented certain new and useful Improvements in Axles and Bearings, of which the following is a specification.

My invention relates to an improvement in 10 axles and bearings, and the object is to provide a simple, inexpensive, and effective construction for the purposes sought; and it consists in the main of a straight round wooden axle formed or turned in three successively- 15 diminishing diameters toward the extreme end, in combination with a round metal skein also formed both inside and outside in three diminishing diameters and adapted to receive and fit the end of the axle, roller-bearings 20 fitted to and encircling the bearing of the skein, a-wheel-hub inclosing and adapted to turn on the bearings, a removable nut, and means for securing the skein to the axle at both its inner and outer ends.

25 My invention still further consists in certain novel features of construction and combinations of parts, which will be hereinafter more fully described, and particularly pointed out in the claim.

30 In the accompanying drawings, Figure 1 is a longitudinal sectional view of the axle and skein, showing the means for fastening the two together at the inner and outer ends and the rollers in position. In this figure the hub is also shown in section, as well as the nut. Fig. 2 is a view showing the hub partly removed, which is the position of parts when oiling; and Fig. 3 is a detached view of the nut.

35 A represents a wooden axle formed or turned 40 on three diminishing diameters marked 1, 2, and 3, respectively, with the shoulders 4 and 5 between the portions 1 and 2 and 2 and 3, respectively. These portions are round or cylindrical, or, in other words, are perfectly 45 straight and without taper.

B is the skein. This skein conforms in its interior to the shape of the axle, its bore fitting the three diminishing diameters of the wooden axle securely and abutting snugly 50 against the shoulders 4 and 5. Although the skein fits so tightly that it is held rigidly in

place by friction, yet, nevertheless, as an additional means for securing it in place one or more bolts 6 6 are passed through the inner end of the skein, where they are held by nuts 55 7 7 in the usual manner, after which their ends are upset, or, it is needless to say, although perfectly obvious, that rivets or screws could be substituted for these bolts. A nail 60 or screw 8 is driven or screwed longitudinally into the extreme outer end of the skein and axle, and thus by means of the screws, bolts, rivets, nails, or what not at the two extreme ends of the skein the latter is securely held on the axle against the possibility of lateral 65 or longitudinal movement, or, in fact, any movement whatever of the skein with respect to the axle on which it is secured. It might also be said that the tendency of all of these fastening means is to spread the wood inside 70 of the steel or metal skein and in that way also greatly increasing the rigidity with which said parts are held together.

The intermediate straight or cylindrical portion of the skein constitutes the bearing 75 upon which the hub turns, and entirely encircling this bearing portion and interposed between it and the bore of the hub are the roller-bearings 9 9, which extend the entire length of this bearing portion, abutting at 80 their inner ends at the inner shoulder 10 of the skein and extending at the other ends flush with the outer shoulder 11 of the skein. The nut 12 screws onto the outer end of the skein and its flange 13 is of sufficient diameter to inclose the ends of the roller-bearing, the nut having that additional function besides the ordinary ones of a hub-nut.

To oil or grease the hub, it is merely necessary to remove it part way, as indicated in 90 Fig. 2, the hub in that way retaining the roller-bearings against displacement, as its bore is perfectly cylindrical, and it therefore fits these bearings when entirely on or partly removed.

95 From the foregoing it will be seen that the roller-bearings bear throughout their entire length upon the intermediate bearing portion of the skein and likewise upon the entire internal area of the hub, nothing being 100 required in the way of a washer or other auxiliary means to retain the roller-bearings in

position temporarily or otherwise. In this way the entire interior of the hub bears equally and uniformly upon the rollers, and the rollers in turn bear equally and uniformly throughout their entire lengths upon the intermediate bearing portion of the skein.

The construction is a thoroughly practical one, as it can readily be seen that the parts are so constructed as to be possessed of superior strength. At the same time the several parts are simple, and hubs constructed in this way not only have a minimum of friction, but also they remain lubricated for a long period and do not wear out easily or become inoperative with wear.

It is evident that slight changes might be resorted to in the form and arrangement of the several parts described without departing from the spirit and scope of my invention, and hence I do not wish to limit myself to the exact construction herein set forth; but,

Having thus described my invention, what

I claim as new, and desire to secure by Letters Patent, is—

The combination with a wooden axle having the end formed with a series of diminishing diameters and a skein of corresponding form fitted thereon and secured at both ends to the axle, the intermediate portion of the skein being cylindrical in form, of roller-bearings surrounding the cylindrical portion, a hub having a cylindrical bore which surrounds and turns upon the rollers, said rollers and hub abutting the enlarged end of the skein and a nut screwed onto the portion of the skein having a smaller diameter, with its flange abutting the outer ends of the cylindrical portion of the skein and reaching over the outer end of the rollers.

EUGENE E. STUVER.

In presence of—

CHARLES McNUTT,

PERRY L. VAN CLEVE.
